UNITED STATES PATENT OFFICE.

ARTHUR L. RUSSELL, OF HYDE PARK, MASSACHUSETTS, ASSIGNOR TO UNITED SHOE MACHINERY COMPANY, OF PATERSON, NEW JERSEY, A CORPORATION OF NEW JERSEY.

METHOD OF LASTING.

1,217,070.

Specification of Letters Patent. Patented Feb. 20, 1917.

Original application filed October 5, 1910, Serial No. 585,431. Divided and this application filed May 26, 1915. Serial No. 30,661.

To all whom it may concern:

Be it known that I, ARTHUR L. RUSSELL, a citizen of the United States, residing at Hyde Park, in the county of Norfolk and State of Massachusetts, have invented certain Improvements in Methods of Lasting, of which the following description, in connection with the accompanying drawings, is a specification, like reference characters on the drawings indicating like parts in the several figures.

The general object of the present invention is an improvement in methods of making boots and shoes, the invention being herein shown as employed in the manufacture of shoes of the welt type although it will be apparent that the invention in some of its aspects is also applicable to the manufacture of shoes of other types. This application is a division of application Serial No. 585,431, filed Oct. 5, 1910, for machines for use in the manufacture of shoes, upon which United States Letters Patent No. 1,163,597 were granted Dec. 7, 1915.

According to the usual practice in lasting the sides of shoes a portion of an upper is stretched over a last and that portion of the upper is secured to an innersole by a fastening inserted through it into the inner-sole with a minimum of loss of the tension on the stretched portion of the upper. In one aspect the present invention contemplates overworking two laterally adjacent portions of an upper and fastening the portion of upper which is located between such portions. The laterally adjacent portions acted upon in overworking the upper may be stretched to any desired extent and they will transmit a less degree of tension to the portion located between them. If the more moderately tensioned portion of upper is then fastened and the more highly tensioned portions are thereafter allowed to react the latter portions, assuming them to be located a suitable distance apart, will retain a degree of tension approximating that of the fastened portion and a lasted shoe will be produced having adjacent portions of its upper under approximately the same tension. This method produces shoes which are comfortable because the uniformly tensioned condi-

tion of the different portions of the upper allows the shoe to conform to the shape of the wearer's foot as a shoe cannot do if portions of the upper have been fastened as heretofore under maximum lasting tension, although intermediate portions of the upper may be comparatively loose.

In another of its aspects the invention comprises working an upper over a last at laterally adjacent points and fastening the upper at an intermediate point in lasted relation to an innersole lip by a staple driven through the upper and lip transversely of the lip. In this aspect the method of this invention is an improvement upon a method invented by James Cavanagh and claimed in application Serial No. 862,211, filed September 17, 1914, upon which United States Letters Patent No. 1,163,596 were granted Dec. 7, 1915, which comprises working successive portions of an upper over a last by repeated operations and securing each portion of upper as it is overworked to the lip of an innersole by driving a staple through the upper and lip in a direction transverse to the lip. The improvement over that process which consists in locating a staple fastening in the more moderately tensioned portion of the upper between the points at which maximum tension is applied has the advantage that it makes possible the fastening of the upper with adequate security by the use of a staple of finer wire than that which would be required to hold the upper at a point of maximum tension. This is important because it renders practicable the lasting and staple fastening of work from which the staples would pull out if they were inserted at points subjected to maximum lasting tension. The use of finer wire staples made possible by this invention is also important because it reduces the danger of damage to the shoe or injury to the machines if the staples are encountered by the operating tools of the welt and the in-seam trimmer. An advantageous manner of practising the new method is to overwork a portion of the upper by rubbing it up the side of a last and across the edge of the last and then to press a laterally adjacent portion of the margin of the upper over

the innersole and fasten it and then to advance the shoe and repeat the rubbing, pressing and fastening for progressively lasting the shoe. This invention is of particular utility in lasting the sides of shoes.

The invention will more clearly appear from the following description which sets forth how it may be practised with the aid of the form of apparatus which is shown 10 and described in the said Patent No. 1,163,597.

Having reference now to the accompanying drawings which illustrate an advantageous manner of carrying out the invention, 15 Figure 1 is a plan view of the bottom face of the fore part of a pulled over shoe one side of which is partially lasted according to the method of this invention;

Fig. 2 shows in vertical section through 20 the shoe two successive positions assumed during the lasting and fastening operation by the work relatively to an illustrative example of lasting and fastening instrumentalities;

25 Fig. 3 shows in section the preferred location of the fastenings with relation to the subsequently applied welt and to the plane in which the inseam trimmer cuts off the surplus stock after welting and preparation to sole laying. The improvements in methods of making shoes which constitutes the present invention will be described in detail. It will be understood, however, that the various means employed may vary 30 widely and that the order and nature of the steps of the method described may be modified somewhat without departing from the invention.

In accordance with the illustrated mode 40 of practising the invention, which is now to be described with especial reference to its use in the manufacture of welt shoes, an innersole 2 is provided with an upstanding lip or rib 3 and a feather 4 into the angle 45 of union between which it is usual to force the upper during the lasting operation. The innersole is attached to the bottom of a last 6 and the upper materials are assembled and the shoe pulled over and secured in pulled 50 over position by tacks, all as illustrated in Fig. 1. The shoe is then side lasted and the upper simultaneously fastened progressively as the lasting proceeds, usually from the shank toward the toe. The lasting and 55 fastening operation may if desired be continued around the toe of the shoe, although it is usual to perform the toe lasting by a different process and to bind it in lasted position by a wire because of the bulky nature 60 of the toe portion of the upper and the curvature of the last edge over which the toe portion of the upper must be worked and secured. After the shoe is side lasted according to the present method it may be ended 65 lasted in the usual way and the upper and

innersole and welt will then be united with stitches. After the stitching operation the inseam is trimmed.

In carrying out the invention I work a portion of the upper over the last and then 70 press a laterally adjacent portion of the margin of the upper over the innersole and fasten it and then advance the shoe and repeat the operation for progressively lasting the shoe. I preferably overwork two laterally adjacent portions of the upper and while holding said portions under tension press the more moderately tensioned portion of upper located between them into close contact with the lip of the innersole 80 and permanently unite the upper and the lip by inserting therethrough and clenching a staple of fine wire. I then allow the more highly tensioned portions of the upper to react. This invention may be practised with 85 the aid of hand tools but I preferably employ an organized machine especially constructed to facilitate the lasting of the upper and the insertion of appropriate staples in the way described. Such a machine is 90 disclosed in said Patent No. 1,163,597, and in the use of that machine two laterally adjacent portions of the upper are tensioned up the side of the last by two continuously running friction lasting belts 10, 10, moving 95 upwardly and mounted to yield under pressure of the side of the shoe against them until the shoe reaches a position to engage two other lasting devices which are marked 65, 65 on the drawing and are located between 100 the belts. The shoe can be rolled from the first position to the second position of Fig. 2 to cause the lasting belts to draw said portions of the upper over the edge of the last and hold them under tension. The upper is 105 forced inwardly over the feather and against the lip of the innersole by pressure of the shoe laterally against the lasting devices 65 and the stationary lasting member 100 which engages the upper between the devices 110 65 as shown best in Fig. 1. It is obvious that the portion of upper located between the lasting devices 10, 65 and 65, 10 will be more moderately tensioned than the portions 115 acted upon by said devices. It is this more moderately tensioned portion of the upper which is acted upon by the member 100 which is a stationary lasting device in that by pressure of the shoe against it the more moderately tensioned portion of the upper 120 is forced into lasted position. Said member 100 is also the nose of the stapling mechanism and through it the driver 106 operates to insert a staple transversely of the channel lip through the upper and said lip to fasten 125 the more moderately tensioned portion of the upper in lasted position. The channel lip is backed up against the action of lasting devices 65 by pressers 140 and against the action of the driver 106 by the staple 130.

- clenching anvil 130, and the operator is assisted in presenting the shoe at the right elevation by work guides 30. I find it advantageous to weaken the bar of the staple 5 so that if the needle of the welter engages it the staple bar will break without damaging the shoe or injuring the needle and I weaken the staple by forming a nick in the bar or head portion adjacent to one or both 10 ends of the bar. This nick is conveniently made by fins or projections 114 on the end face of the staple driver bar 106. The complete organization of this machine, including the means for yieldingly mounting and 15 for operating the lasting members 10, the arrangement of the lasting members 65 movable backwardly along the side edges of the staple nose 100 in response to pressure of the shoe and against yielding resistance, the 20 connections through which said members 65 start the stapling mechanism during such movement and cause the work clamps 140 and the anvil 130 to engage the shoe in time relation with the operation of the staple 25 driver, are all fully described and shown in the former of the two patents referred to and do not require further explanation. After the side lasting and stapling operation the toe and heel of the shoe are lasted 30 and the operation of uniting the upper, the innersole lip and the welt by inseam stitching is performed and then the inseam is trimmed. The staples are above the path of the needle and below the plane in which the 35 inseam can advantageously be trimmed, so that they do not interfere with the operation of the welter needle or with the inseam trimming operation and remain in the shoe as individual permanent fastenings.
- 40 It will be noted that an advantage of the method of making shoes herein described is that the fastenings are inserted in a relatively moderately tensioned portion of the upper laterally adjacent to a highly tensioned portion and that the highly tensioned portion is allowed to react so that the upper is fastened under moderate tension which is more nearly uniform at all 45 points along the portion of the shoe which is lasted in accordance with this method than an upper is when each highly tensioned portion of upper is fastened under maximum tension and the more moderately tensioned adjacent portions are unsecured by 50 lasting fastenings.
- Having thus fully described the invention, what I claim as new, and desire to secure by Letters Patent of the United States is:—
- 60 1. That improvement in methods of making shoes which consists in progressively lasting the shoe by successive operations applied to adjacent parts of the upper one after another, each of which operations comprises stretching two laterally adjacent por- 65 tions of an upper up the side of a last and while continuously holding said portions under tension fastening the more moderately tensioned portion of upper located between said portions and then allowing the more highly tensioned portions of the upper to react. 70
2. That improvement in methods of making shoes which comprises tensioning the upper at two laterally adjacent points, pressing into lasted position and, while continuing the pressure fastening the more moderately tensioned portion of upper between said points, and then permitting the upper to react at the more highly tensioned points 75 and repeating the operation on successive portions of the shoe to last and fasten the shoe progressively. 80
3. That improvement in methods of making welt shoes which comprises drawing the upper up the side and over the edge of an inverted last at two laterally adjacent points and uninterruptedly holding the upper under tension at said points while forcing into lasted relation to the channel lip of an 85 innersole and there fastening the more moderately tensioned portion of the upper located between said points, then allowing the upper to react, and repeating the operation on successive portions of the shoe to 90 last and fasten the shoe progressively. 95
4. That improvement in methods of making welt shoes which comprises tensioning an upper at two laterally adjacent points at a time, forcing the portion of upper between 100 said two points into the angle of union between the lip and feather of an innersole and uniting it to said lip by inserting through the upper and said lip an individual permanent fastening that will not interfere 105 with the operation of the welter needle or with the inseam trimming operation, repeating the operation on successive portions of the shoe to last and fasten the shoe progressively, and subsequently attaching a welt to 110 the upper and innersole by stitching. 115
5. That improvement in methods of making welt shoes which comprises working an upper over a last at two laterally adjacent points, pressing the upper and the channel lip of the innersole into close contact with each other between said two points, permanently uniting the upper and lip while in this relation by inserting therethrough and 120 clenching a staple of fine wire, and then uniting the welt, upper and innersole with stitches. 125
6. That improvement in methods of making shoes which comprises working successive portions of an upper over a last and securing the upper by repeated operations each of which repeated operations consist in tensioning the upper at two laterally adjacent points simultaneously and inserting a fastening between said points through the 130

upper and the lip of an innersole in a direction transverse to the lip.

7. That improvement in methods of making shoes which comprises working successive portions of an upper over a last by repeated operations and securing each portion of the upper to the lip of an innersole as it is overworked by driving a staple through the upper and lip in a direction transverse to the lip and so weakening the bar of the staple that it will break readily if the needle or awl of the welt sewing machine encounters it in the welding operation.

15 8. That improvement in methods of making shoes which comprises rubbing an upper up the side of a last at two laterally adjacent points; then pressing the margin of the upper between said points over an innersole on the last bottom and fastening it; and then advancing the shoe and repeating the rubbing, pressing, and fastening for progressively lasting the shoe.

25 9. That improvement in methods of making shoes which comprises rubbing a portion of an upper up the side of a last and across its edge; then pressing a laterally adjacent portion of the margin of the upper over an innersole on the last bottom and fastening it; and then advancing the shoe and repeating the rubbing, pressing and fastening for progressively lasting the shoe.

35 10. That improvement in methods of making welt shoes which comprises working a portion of the upper over a last, pressing a laterally adjacent portion of the upper and the channel lip of the innersole into close contact with each other, permanently uniting the upper and lip while in this relation by inserting therethrough and clinching a staple of fine wire, repeating the operation to last and fasten successive portions of the shoe progressively, and thereafter uniting the innersole lip, the upper and a 45 welt with stitches.

11. In the art of making shoes, the im-

provement which consists in providing an innersole with an upstanding lip, and simultaneously side lasting the upper and stapling the upper to said upstanding lip of the 50 innersole, said upper being pulled relative to the last and the innersole at points positioned at opposite sides of the point of insertion of the staple.

12. The process herein described of making shoes which consists in providing an innersole with an upstanding lip, attaching said innersole to a last, drawing the upper around the last, and stapling the edge portion of the upper to the upstanding lip of 60 the innersole and simultaneously therewith side lasting the upper by drawing it at two points positioned at the respective sides of insertion of the staple fastenings.

13. The process herein described of making shoes which consists in providing an innersole with an upstanding lip, attaching said innersole to a last, pulling over an upper relative to the last, and directly thereafter stapling the upper to the upstanding 70 lip of the innersole and simultaneously with said stapling operation side lasting the upper by pulling it over the innersole and last at points positioned on opposite sides of the point of insertion of the staple fastening. 75

14. The process herein described of making shoes which consists in providing an innersole with an upstanding lip, attaching said innersole to a last, pulling over an upper relative to the last, and directly thereafter stapling the upper to the upstanding 80 lip of the innersole and simultaneously with said stapling operation side lasting the upper by pulling the free edges of said upper at two points over the last and the inner- 85 sole, the points of strain being at opposite sides of the insertion of the staple fastening and the direction of the pull being against and over the edge of the innersole.

In testimony, whereof I have signed my 90 name to this specification.

ARTHUR L. RUSSELL.

It is hereby certified that in Letters Patent No. 1,217,070, granted February 20, 1917, upon the application of Arthur L. Russell, of Hyde Park, Massachusetts, for an improvement in "Methods of Lasting," an error appears in the printed specification requiring correction as follows: Page 4, line 13, claim 7, for the word "welding" read *welting*; and that the said Letters Patent should be read with this correction therein that the same may conform to the record of the case in the Patent Office.

Signed and sealed this 24th day of April, A. D., 1917.

[SEAL.]

F. W. H. CLAY,

Acting Commissioner of Patents.

CL 12—145.
